(74) Attorney, Agent, or Firm — EcoTech Law Group,
P.C.(57) **CLAIM**

The ornamental design for a beam clamp, as shown.

DESCRIPTION

FIG. 1 is a perspective view of a beam clamp according to the present invention;

FIG. 2: is a left side view of the beam clamp of FIG. 1;

FIG. 3: is a front view of the beam clamp of FIG. 1;

FIG. 4: is a rear view of the beam clamp of FIG. 1;

FIG. 5: is a top view of the beam clamp of FIG. 1; and,

FIG. 6: is a bottom view of the beam clamp of FIG. 1.
